UNITED STATES PATENT OFFICE

2,494,094

EXERCISING STOOL

Walter G. Horstman, Des Moines, Iowa

Application June 19, 1946, Serial No. 677,739

2 Claims. (Cl. 272—58)

1

This invention relates generally to health aiding devices and in particular to an exercising device for stimulating the flow of digestive acids in the intestinal tract to aid a proper food digestion.

Gastric acidity oftentimes occurs because of an accumulation of digestive acids in what may be termed "pockets" in the intestinal tract. Through the exercising of the abdominal muscles the flow of the digestive acids through the intestinal tracts is appreciably increased so as to reduce or, in some cases, to completely eliminate such accumulation.

It is an object of this invention, therefore, to provide an improved exercising device for stimulating the flow of digestive acids through the intestinal tract.

Another object of this invention is to provide an exercising device for aiding the natural digestion of food, by reducing the accumulation of digestive acids in parts of the intestinal tract.

Yet another object of this invention is to provide an exercising device which is adapted to be used as a piece of home furniture, when not utilized for exercising purposes.

A feature of this invention is found in the provision of an exercising device in which means are provided for connecting an upright coil spring between a body supporting member and a base member, such that the supporting member is capable of being moved upwardly, downwardly and laterally, relative to the base member, without the device being upset, and with the axis of the spring always being returnable to a normal position in a substantially vertical plane.

Further objects, features and advantages of this invention will become apparent from the following description when taken in connection with the accompanying drawings in which:

Fig. 1 is a side elevation of the exercising device of this invention illustrating the manner of its use;

Fig. 2 is a foreshortened enlarged sectional view as seen on the line 2—2 in Fig. 1;

Fig. 3 is a fragmentary perspective view of the body supporting member;

Fig. 4 is a fragmentary perspective view of the base member; and

Fig. 5 is a perspective view of a clamp member forming part of the means for connecting an upright coil spring between the body supporting and base members.

With reference to the drawings the exercising device of this invention is illustrated in Figs. 1

2

and 2 as including a base member 10, a body supporting member 11, and a coil spring 12.

The base 10 (Figs. 2 and 4) is of a hollow construction and integrally formed from a single piece of material with a flat substantially rectangular shaped top member 13 having each side thereof formed with an outwardly and downwardly extended flange or leg 14. The lower end of each leg 14 is bent inwardly to form a foot 16. As best appears in Fig. 4 the adjacent ends 17 of the flanges 14 are spaced apart from each other, to form open corners for the base 10, while the adjacent ends 18 of the foot members 16 are welded together in a mitre joint. It is seen, therefore, that the legs 16 are continuous about the lower peripheral side of the base 10.

Arranged substantially centrally within the flat top member 13 is an annular depression 19 (Figs. 2 and 4) of a size and shape adapted to receive the lower side of the bottom end coil 21 of the spring 12. As best appears in Fig. 2 the end coil 21 is arranged in a transverse plane substantially normal to the axis 22 of the spring 12.

25 The end coil 21 is clamped within the annular depression 19 by means including a disc shape clamp member 23 (Figs. 2 and 5), having a downwardly and outwardly curved peripheral rim 24 adapted to fit over the top side of the end coil 21. Closely adjacent to the curved rim 24 and extended through the member 23 is an angularly extended slot 26 through which the spring 12 is insertable, whereby the clamp member 23 is capable of being moved axially of the spring 12, while in a position concentric with the spring axis.

The clamp member 23 is arranged opposite the annular depression 19, in the base member 10, with the curved rim 24 in a cooperating relation with the depression 19 so as to substantially completely enclose the end coil 21. A bolt 27, extended through countersunk openings 28 and 29 provided in the clamp member 23 and base 10, respectively, clamps the member 23 against the flat top member 13. The holes 28 and 29 are countersunk in reverse directions, so that the inner adjacent ends of the countersunk portions 31 and 32 in the clamp member 23 and flat top member 13, respectively, are in substantial abutting engagement when the clamp member rim 24 and the annular depression 19 are in a mating relation. The head of the bolt 27 is received within the countersunk portion 31, while a nut 33 therefor is received within the countersunk portion 32 in the base 10.

It is seen, therefore, that the end coil 21 is firmly secured against movement relative to the base member 10 substantially in the plane of the flat top member 13, whereby the spring 12 is supported in an upright position with its axis 22 in a substantially vertical plane.

The body supporting member 11 is of a hollow construction and integrally formed with a flat substantially rectangularly shaped top member 36 having a downwardly and outwardly extended straight flange 37 which terminates in an inwardly bent rim 38 (Figs. 2 and 4). Located centrally of the flat top member 36 is an annular rib 39 for receiving the upper side of the top end coil 41 of the spring 12.

A clamp member 23, similar in all respects to the clamp member 23 described in connection with the bottom end coil 21, has its peripheral rim 24 adapted to receive the bottom side of the top coil 41. The top coil 41 is positioned with its top side within the rib 39 and the top clamp is secured against the bottom side of the flat top member 36 by a clamping bolt 27 extended through the countersunk hole 28 in the clamp member 23, and a countersunk hole 42 in the flat member 36.

The top coil 41 is also arranged in a transverse plane substantially normal to the spring axis 22 whereby the body supporting member 11, in its clamped assembly with the spring 12, has the top flat member 36 thereof in a substantially horizontal plane. It is seen, therefore, that the clamp members 23 are of a like construction and similarly assembled with the base member 10 and body supporting member 11 to connect the end coils 21 and 41, respectively, with such members.

In the use of the exercising device of this invention, and as is illustrated in Fig. 1, a person merely lays himself across the device with his abdominal portion 44 resting on the body supporting member 11 and with both his feet 46 and hands 47 in engagement with the floor surface. By manipulation of his body, and applying a downward pressure on the exercising device, the spring 12 is compressed and permitted to expand concurrently with a lateral or sidewise movement in any direction of the body supporting member 11.

This action massages and exercises the abdominal muscles and effects a reaction in the digestive system to aid the flow of digestive acids through the intestinal tract. By virtue of the substantial full bearing engagement of the bottom coil 21 with the clamp 23 and the base 10, and the clamping of such coil in a fixed position relative to the base, the exercising device is maintained stable against being upset, at any moved position of the spring 12. Also, because of the rigid securing of the end coil 21 in substantially the plane of the flat top member 13, and the initial arrangement of the end coil 21 in a plane substantially normal to the spring axis 22, the spring 12 is returnable to an upright position with its axis 22 in a substantially vertical plane when the weight of a person is removed from the body supporting member 11.

In order to eliminate any objectionable clicking noises when the spring 12 is compressed, by virtue of the coil 48 next adjacent to the bottom coil 21

coming into contact with the top side of the clamp member 23, the connecting member 49 between the spring coils 21 and 48 (Figs. 1 and 2) is arranged in an upright position at any angle of substantially forty-five degrees relative to the plane of the end coil 21. As a result sufficient space is provided between the coil 48 and the clamp member 23, at all moved positions of the spring 12, to eliminate any contact engagement between such parts.

When the device is not in use it may be provided with a suitable covering material and used as a stool in a bedroom, or as a foot rest.

Although the invention has been described with respect to a preferred embodiment thereof it is to be understood that it is not to be so limited since changes and modifications can be made therein which are within the full intended scope of this invention as defined by the appended claims.

I claim:

1. An exercising device comprising a base member, a body supporting member, an upright coil spring connected between said two members having an end coil arranged in a plane substantially normal to the axis of said spring, means for connecting said end coil with one of said two members including a clamp member having an annular curved portion adapted to receive one side of said end coil therein, with said one member having an annularly depressed portion adapted to receive the other side of said end coil, with said clamp member being positionable opposite said depressed portion to substantially close said end coil therebetween, and means for clamping said end coil between said depressed portion and said clamp member.
2. An exercising device comprising a base member, a body supporting member, an upright coil spring connected between said two members having the lower end coil thereof arranged in a plane substantially normal to the axis of said spring, said base member having an annular depressed portion therein adapted to receive one side of said end coil, a clamp member having an annular curved portion adapted to receive the other side of said end coil, means for clamping said end coil between said two portions, and a connecting member between said end coil and the next adjacent spring coil extended upwardly from said clamp member, whereby said next adjacent coil, on compression of said spring, is out of contact engagement with said clamp member.
